D. S. SEYMOUR,
PRESSER FOOT MECHANISM FOR SEWING MACHINES,
APPLICATION FILED APR. 6, 1916.

Patented Apr. 15, 1919.

2 SHEETS—SHEET 2.

UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

PRESSER-FOOT MECHANISM FOR SEWING-MACHINES.

1,300,885.

Specification of Letters Patent. Patented Apr. 15, 1919.

Original application filed December 27, 1915, Serial No. 68,787. Divided and this application filed April 6, 1916. Serial No. 89,314.

To all whom it may concern:

Be it known that I, DUDLEY S. SEYMOUR, a citizen of the United States, residing at Oak Park, in the county of Cook, State of Illinois, have invented certain new and useful Improvements in Presser-Foot Mechanism for Sewing-Machines, of which the following is a description, reference being had to the accompanying drawing and to the figures of reference marked thereon.

The invention relates to new and useful improvements in presser foot mechanism for sewing machines, and more particularly to the means for placing the presser foot under pressure.

An object of the invention is to provide a sewing machine having a supporting standard and an overhanging arm carrying the presser foot with a leaf spring for forcing the presser foot toward the work support, which leaf spring is of greater length than the distance between the presser bar and the outer face of the standard whereby a more uniform pressure of the foot against the material on the work support for varying thicknesses of material may be secured.

In the drawings, which show by way of illustration one embodiment of the invention:

Figure 1 in a view, partly in section and partly in front elevation, showing a machine having my improved presser foot mechanism applied thereto;

Fig. 2 is a view of a portion of the head of a machine with the face plate removed;

Fig. 3 is a sectional view on the line 3—3 of Fig. 2; and

Fig. 4 is a sectional view on the line 4—4 of Fig. 3.

In the drawings, I have shown a sewing machine consisting of a supporting bed 1 carrying a work support 2 and a standard 3. Said standard carries an overhanging arm 4 having a head 5 at its free end in which reciprocates the needle bar 6. The needle bar 6 is reciprocated by a lever 7 which is connected to the needle bar by a link 8. This needle lever 7 is oscillated by an eccentric strap 9 which coöperates with an eccentric on the main shaft 10. The standard 3 and the overhanging arm 4 are hollow, and the needle lever is located within the arm and standard. The operating mechanism for the needle lever is also located within

the standard. It will be understood that there is a cover plate fitting the upper portion of the standard and the front portion of the overhanging arm, as shown in Fig. 1, so as to form an inclosed standard and arm.

The needle bar carries a needle 11, and a looper 12 coöperates with this needle beneath, the work support 2 and a spreader 13 coöperates with the looper and the needle. The material is held on the work support by a presser foot 14 which is fixed to the lower end of a presser bar 15. An auxiliary foot 16 is carried by an auxiliary bar 17. Rigidly clamped to the presser bar 15 is a bracket 18. The set-screws 19 passing through the bracket engage the bar and hold the bracket in fixed position on the bar. This bracket projects laterally and is formed with a sleeve 20 which freely engages the auxiliary bar 17. Said bracket also has a projecting arm 21 on which rests a leaf spring 22. Said arm 21 has upwardly projecting ledges 23 between which the end of the leaf spring 22 extends.

The auxiliary bar 17 is provided with a collar 24 which extends laterally and is forked at 25 so as to receive an upwardly projecting portion 26 formed on the bracket 18. A spring 27 bears against the upper face of the collar 24 at its lower end and the upper end of this spring bears against the head of the machine. This spring 27 forces the bar 17 downwardly. The leaf spring 22 extends along and within the upper portion of the hollow arm 4 and at 28 said spring is curved downwardly so that the end 29 thereof seats in a supporting abutment 30 attached to the inner face of the outer wall of the standard 3. A screw 31 is threaded through the upper wall of the arm and standard and bears on said spring 22 adjacent the curved portion thereof so as to place said spring under tension. From the above statement, it will be apparent that the spring 22 is longer than the distance between the presser bar and the outer wall of the standard 3. By making the spring of this greater length, a much more even yielding action is imparted to the foot controlled by the spring.

The presser bars may be lifted by an arm 32 mounted on a shaft 33 and extending underneath the arm 21 on the bracket 18. A lever 34 which may be connected to a suit-

able treadle is connected to the shaft 33. A downward movement at the outer end of the lever 34 raises the arm 32; this raises the bracket 18 and both presser bars 15 and 17. 5 The presser bars may also be raised by a hand lever 35 which is pivoted at 36 to the head of the machine and is provided with a cam 37 which extends underneath a projecting pin 38 carried by a collar 39 secured to the presser bar 15. By swinging the hand lever in an upward direction, the cam 37 will raise the collar 39 and presser bar 15, and this, through the bracket 18, will raise the presser bar 17.

10 15 This application is a division of my pending application, Serial No. 68,787, filed December 27, 1915.

It is obvious that minor changes in the details of construction and the arrangement of parts may be made without departing from the spirit of the invention, as set forth in the appended claims.

Having thus described the invention, what is claimed as new is:—

20 25 1. The combination of a hollow standard, a hollow overhanging arm, a presser foot, a presser bar carrying said foot, a leaf spring, a bearing carried by said presser bar on which one end of said spring rests, a supporting abutment attached to the inner face of the outer wall of the standard and supporting the other end of said leaf spring, and means engaging the spring between its ends for placing the same under tension.

Copies of this patent may be obtained for five cents each, by addressing the "Commissioner of Patents, Washington, D. C."

2. The combination of a standard, an overhanging arm, a presser foot, a presser bar carrying said foot, a leaf spring, said spring having a horizontal portion, a curved portion and a vertical portion, a bearing on said presser bar on which the free end of the horizontal portion of said spring rests, an abutment carried by the standard for supporting the other end of the spring, means engaging the spring between its ends for placing the same under tension for causing 45 said spring to force the presser foot downwardly.

3. The combination of a hollow standard, a hollow overhanging arm, a presser bar, a presser foot carried thereby, a leaf spring 50 located in said hollow arm, said leaf spring having a horizontal portion, a curved portion and a vertical portion, a bearing carried by the presser bar on which the free end of said horizontal portion rests, a supporting 55 abutment carried on the inner face of the outer wall of the standard on which the free end of the vertical portion rests, and a screw passing through the upper wall of the overhanging arm and engaging said spring adjacent the curved portion therein for placing the same under tension.

In testimony whereof, I affix my signature, in the presence of two witnesses.

DUDLEY S. SEYMOUR.
